UNITED STATES PATENT OFFICE

DANIEL W. B. KURTZ, JR., OF COLUMBIA, MISSOURI

BILL FOLD OR PURSE

Application filed May 2, 1928, Serial No. 274,440. Renewed April 21, 1931.

This invention relates to pocket bill-folds, and more particularly, to pocket bill-folds adapted to retain bills, stamps and miscellaneous cards in an orderly assorted manner so that the contents of the bill-fold will be readily apparent and easily extracted as desired.

An object of the present invention is to provide a bill-fold of the character indicated of an improved and simplified structure involving the use of a minimum number of parts, and a minimum amount of sewing to present a very efficient device.

A further object of the invention is to provide a bill-fold having means for displaying cards of different sizes while securely retaining the same.

A further object of the invention is to provide a bill-fold having an unexpected, or what may be termed a concealed pocket.

Further objects will more fully appear in connection with the following description.

Two sheets of drawings accompany this application as a part hereof, in which like reference numerals indicate like parts throughout.

Figure 1 is a plan view of the principal blank entering into the construction of the improved bill-fold;

Figure 2 is a plan of a subsidiary blank adapted for use in separating bills of different denominations;

Figure 3 is a plan of a similar blank to that shown in Figure 2, used for a similar purpose;

Figure 4 is a plan of the blank used for the stamp pocket;

Figure 5 is a plan view of a piece of transparent material used in making the card window;

Figure 6 is a plan view of a second transparent blank used in connection with the blank of Figure 5 in forming the card pocket window;

Figure 7 is a plan view of the bill-fold assembled;

Figure 8 is a plan view of the bill-fold assembled and folded once for pocket use;

Figure 9 is a plan view of the bill-fold assembled and folded twice for pocket use;

Figure 10 is a top plan view, taken on Figure 7; and

Figure 11 is a side elevation, taken on Figure 7.

In accordance with the present invention, the principal blank for the bill-fold, which may be of leather, leatherette, or other suitable flexible material, is formed in a U-shape, as indicated in Figure 1, having one leg E longer than the other leg F. The leg E is substantially twice as long as the part connecting the legs indicated at A—B is wide. The upper part of leg E is divided into two parts C and D by a slot 5 cut from the blank, and the part C has a window 4 cut away. The short leg F is provided with a window 6, cut therefrom.

To close window 4, two transparent members 12 and 13 are provided, (see Figure 5) the member 12 being merely a rectangular piece of isinglass, celluloid, or the like, while the member 13 has cut therefrom a window 18. These two transparent members are placed one upon the other and secured over window 4 by a marginal seam 19 extending around the outer long edge and the two short ends. The transparent pieces are arranged, the solid member 12 outermost and the member 13 having window 18 innermost.

By this construction it will be apparent that visiting cards or the like of different sizes may be securely held under window 4, the larger cards positioned between members 12 and 13, and smaller cards positioned under member 13.

Leaves for separating bills of different denominations are provided, each leaf being substantially rectangular, (see Figures 2 and 3) having at one corner an upstanding tab 14—15 upon which may be inscribed the denomination of the bills to be found immediately behind the particular leaf.

These leaves are of different lengths and widths, the leaf G, for the smaller bills, being provided with a window 7 extending from the bottom edge upwards and a window 8 adjacent the end positioned intermediate the edges. The upper edge of leaf G is indicated at f. The leaf H, intended to cover bills of larger denominations, is provided with a

5 window slot 11 extending upward from the bottom edge and two spaced windows 9 and 10 intermediate its long edges; the windows 11 and 9 of leaf H being adapted to coincide with and overlay windows 7 and 8 of leaf G, and both of the windows 7 and 11 of leaves G and H being intended to overlay and coincide with window 6 of the short leg F of the main blank.

10 A small blank I, the upper edge of which is indicated by *h*, is provided to form a stamp pocket and may be suitably inscribed, as indicated, with the word "Stamps" as at 17.

In assembling the improved bill-fold, the 15 lower part of the long leg E of the main blank, (see Figure 1), is folded backward on the line *c*—*c*, thus constituting a back to the upper parts C and D. These superposed parts are then again folded backward on 20 the line *b*—*b*' under the left hand part A, and these parts thus arranged are then connected by a seam 20, connecting the three superposed parts intermediate the parts A and B.

The short leg F of the blank is then folded 25 forwardly on the line *b*'—*b* over the face of the part B. The bill-separating leaves G and H are then placed over parts A and B and under the upturned part F with the lower edges of said leaves G and H along 30 the folded line *b*—*b*, and their right hand ends superposed along the right hand edge *a*—*b* of the part B. The small stamp forming leaf I is then positioned in the lower right hand corner.

35 This assembly is quite clearly illustrated in Figure 7.

At this point, the parts B, H, G, F and I are connected by a seam 21 along the edge *a*—*b*. A third seam 22 connects parts I, F, 40 G and H to parts A and B along the bottom edge *b*—*b*, and a fourth seam 23 connects parts A, C, and E along the line *a*—*b* on the left hand of the bill-fold.

It will be noted that a pocket is formed 45 between the face of part E and the back of part A, having its mouth formed by the edge *c*—*c* and the upper edge of the part A. This unusually positioned pocket is in the nature of a surprise or concealed pocket, and may 50 be conveniently used for bills of large denominations not commonly used.

What I claim is:

1. A bill fold comprising a piece of flexible 55 material of substantially U-shape, having one leg substantially longer than the other and twice as long as the width of the connecting base part, said long leg folded backward on itself and then backward against the connecting base part, and secured to said base part by seams connecting all the edges except that formed by bending said long leg upon itself, to constitute a pocket, and the short leg folded forwardly upon the connecting base part and secured thereto by a seam con-

necting their adjacent free edges to constitute a pocket open on two sides.

2. The structure of claim 1 having a slot cut in the part of the long leg adjacent the base connecting part to form the mouth of 70 two subsidiary pockets.

3. The structure of claim 1 having a slot cut in the part of the long leg adjacent the base connecting part to form the mouth of two subsidiary pockets and a window adjacent 75 said slot to expose the contents of that pocket.

4. The structure of claim 1 having a slot cut in the part of the long leg adjacent the base connecting part to form the mouth of two subsidiary pockets, a window adjacent 80 said slot, said window comprising two superposed transparent members, the inner of said members having a smaller window cut therefrom.

5. The structure of claim 1 with a plurality of bill separating leaves secured between 85 the base connecting part and the short leg by one end and their bottom long edges.

6. The structure of claim 1 with a plurality of bill separating leaves secured between the base connecting part and the short leg, 90 said leaves of varying length.

7. The structure of claim 1 with a plurality of bill separating leaves secured between the base connecting part and the short leg, 95 said leaves of varying lengths, and windows in said short leg and leaves, some of the windows in said parts coinciding.

8. The structure of claim 1 with a pocket forming piece secured to and upon the exposed face of the short leg, by two edges and 100 the same seam that connects the short leg to the base part.

In testimony whereof he affixes his signature.

DANIEL W. B. KURTZ, JR.
